UNITED STATES PATENT OFFICE.

SPENCER HEATH, OF BALTIMORE, MARYLAND.

ADJUSTABLE AND REVERSIBLE PROPELLER.

REISSUED

Application filed December 4, 1919. Serial No. 342,370.

To all whom it may concern:

Be it known that I, SPENCER HEATH, a citizen of the United States, residing at Baltimore, State of Maryland, have invented 5 certain new and useful Improvements in Adjustable and Reversible Propellers, of which the following is a specification.

This invention relates to screw propellers, more particularly to propellers for aircraft, 10 and to that type or class of propellers in which the blades are capable of simultaneous adjustment about their several longitudinal axes in such manner that the pitch of the blades can be varied at will or the action of 15 the blades entirely reversed to any desired degree, all during continuous operation of the propeller either at rest or in flight.

The present invention is of a similar nature to that covered by my copending application Serial No. 308,112, filed July 2, 1919, 20 and its objects are generally the same. Among the features which it comprises, in common with such prior invention are, that the blades are adjusted by engine power delivered to the propeller, manual or bodily 25 force being required only for connecting and disconnecting the operating power; and that there are no operative connections, such as clutch collars, running bearings, or the like, 30 normally in engagement, such connections being established only momentarily during changes in adjustment of the blades.

While the apparatus of my said prior invention is satisfactory for small or medium 35 sized propellers, it has been found somewhat heavy for the larger sizes. A specific object of the present invention, therefore, is to provide a lighter and more compact construction. To this end, I have devised new 40 and simplified operating mechanism, such mechanism including a smaller number of gears, and an improved duplex worm drive for adjusting the blades, and securely locking them in any position.

45 A further object of this invention is to provide a new and improved bearing mechanism to permit rotation of the blades, this mechanism being of the turntable type to avoid the use of long sleeves or sockets for 50 reception of the blades, and thus reduce the weight of the parts.

Another object is to provide a means and method of secure attachment between the several blades and their sockets or ferrules 55 which engage the bearing mechanism.

With the foregoing and other objects in

view I have invented the improved mechanism more particularly described hereinafter, and illustrated by means of the accompanying drawings, which are a part of this 60 specification, and in which:

Fig. 1 is a longitudinal section coincident with the axes of both blades and the shaft.

Fig. 2 is a section on line 2—2 of Fig. 1, 65 part of the gear casing being broken away.

Fig. 3 is an end view of Figs. 1 and 2 shown partly in section through line 3—3 of Fig. 2.

Fig. 4 is a fragmentary side view of Figs. 2 and 3, the gear casing being in section. 70

Fig. 5 is a plan view of brake housing and control lever.

Fig. 6 is a section on line 6—6 of Fig. 5.

Fig. 7 is a section on line 7—7 of Fig. 5.

Fig. 8 is a longitudinal section through a 75 ferrule and blade shank as hitherto made.

Fig. 9 is an end view of Fig. 8.

Fig. 10 is a longitudinal section through a ferrule and blade shank in accordance with the present invention. 80

Fig. 11 is an end view of Fig. 10.

Fig. 12 is a side view of the operating lever, detached.

The parts are designated by corresponding numerals throughout the several views. 85

Referring to the drawings:

1 is the power delivery shaft on and with which the propeller as a whole revolves, and which is secured in the tapered bore of the propeller hub 2 by means of the differential nut 3 which is sufficiently extended in length to protrude slightly beyond the end of hub 2 at which protruding end the nut is provided with holes 4 for reception of a bar to turn the nut. 95

The hub is provided with a cylindrical portion one-half 5 of which is keyed or welded securely to the hub and the other half 6 of which is removably mounted on the outer end of the hub and secured to the part 5 by 100 bolts 7 engaging flanges 8 on parts 5 and 6.

The exterior of the cylindrical portion formed by the union of parts 5 and 6 is of even contour except for the bolt flanges 8; its interior, however, is provided with circular flanges 9 and 12 for reception of ball races 10 and 13 carrying the bearing balls 11 and 14. 105

The blades of the propeller are illustrated two in number but a greater number of 110 blades may be used by the addition of similar corresponding parts. The blades are

preferably of wood, but other materials may be used. The shanks of the blades 20 are secured in ferrules 21, which are of double tapered form, with a constricted central portion 25, as shown in Fig. 1. The shanks are forced into the ferrules under heavy pressure and the ends of the blade shanks are then expanded to fill up the flaring inner ends of the ferrules. Hitherto the expanding of the shanks has been accomplished solely by means of wedges. It has been the practice to make the ends of the shanks cylindrical in form and but little, if any, larger than the smallest portion of the ferrule, as indicated by dotted lines in Fig. 8, and to use a ring wedge 22 concentric with the ferrule to expand the shank. This expansion, by increasing the circumference of the shank, caused radial openings into which were inserted wedges 23. The expansion of the shank by ring wedge 22 caused an outward bending of the wood, with consequent rupture or stress of its fibres at and beyond the toe of the wedge 25 in the small portion of the ferrule, as shown at A in Fig. 8.

In order to avoid this difficulty, I have devised an improved method of securing the shanks in the ferrules.

30 In my improved method, the shank is first prepared with a double tapered form corresponding with the interior of the ferrule. At the entrance to the ferrule, at 24, (see Figs. 8 to 11) the shank is made but 35 slightly larger than the interior of the ferrule. At the throat or smallest diameter of the ferrule as at 25, the shank is made one-quarter to one-half inch larger in diameter than the interior of the ferrule. At 40 the inner end of the ferrule the butt of the shank is made equal or nearly equal in diameter to the inside of the ferrule. The contour of the blade shank before it is inserted in the ferrule is indicated by the 45 dotted lines 28 in Fig. 10. In order to insert the shank it is necessary to reduce its end diameters to that of the restricted portion of the ferrule by compressing the wood. This is accomplished without injury to the 50 parts by coating the shank and ferrule with lead pigment and varnish and imparting a slow rotary motion to the shank while being pressed into the ferrule. By this rotary motion between the parts it is possible to cause a great compression of the wood without requiring very heavy or injurious end pressure to insert the shank. After being inserted, the compressed end 55 of the shank slowly expands to fill up the flaring inner end of the ferrule. This expansion may be hastened or completed by the application of moisture. The circular wedge 22 is now inserted in the butt of the shank for the purpose of compressing the 60 wood against the inner walls of the ferrule. 65

This is accomplished without causing radial openings in the wood and without undue bending or rupture of the fibres at the toe of the circular wedge, for the reason that there is practically no bending due to the 70 wedge. In practice I find it advantageous to insert additional wedges 26, preferably in a radial arrangement both outside and inside of the circular wedge, as shown by Fig. 11, for the purpose of further compressing the wood in the butt end of the shank.

To facilitate insertion of the wood shank the inner walls of the ferrule are made for the most part smooth. This smoothness extends from the entrance end 24 for a distance slightly beyond the throat 25 from which point the inner surface is made rough or slightly serrated or corrugated as indicated at 27 in Fig. 10. This is for the purpose of increasing the security of engagement between the shank and ferrule.

The inner end of ferrule 21 for each blade is provided with a flange 30. On one side of this flange is seated a ball race 31' to contact with race 10 while the other side carries a race 32' coating with race 18. The balls 11 form a simple end thrust bearing and the balls 14 afford a combined end thrust and radial bearing whose function is to preserve 95 concentricity of all the parts and also to take any end thrust that might be caused in case of extreme air pressure causing a large bending moment on the blades.

The entire periphery of flange 30 on each ferrule is provided with worm-gear teeth 31 to engage the worms 32 mounted on the exterior of the hub and engaging through the apertures 33. Worms 32 are driven through shafts 34 by worm gears 35 100 which in turn are driven by worms 36 each of which is integral with its pinion gear 37.

The portion of the hub 2 containing the taper bore for the shaft has an inner extension 39 upon which is journaled a sleeve 40 110 carrying on one end a brake wheel 41 and on its other end the spur gear 42. The sleeve 40 is held in position on the hub by means of the nut 15 threaded on the extension 39 of hub 2. Between brake wheel 115 41 and spur gear 42 the sleeve 40 carries, journaled upon it, a second brake-wheel 43 carrying upon its hub extension 44 a spur gear 45 adjacent to and somewhat larger than spur gear 42 on sleeve 40. Gear 45 120 meshes directly into the two pinions 37. Gear 42 meshes into a pair of idlers 46 which idler gears in turn mesh with pinions 37. It is thus seen that relative rotary motion between either brake wheel and the propeller hub would communicate motion to pinions 37, and pinions 37 would in turn communicate a reverse motion to the other brake wheel. From this it becomes clear 125 that, for a given direction of relative turn- 130

ing of the brake wheels, either forward or reverse motion of pinions 37 may be obtained according as one or other of the brake wheels is turned in the given direction, and pinions 37 communicate this optional motion through worms 36, worm gears 35 and worms 32 to the respective blades.

For convenience in mounting the idlers 10 46, pinions 37 and their associated worms and gears, I provide an assembly ring 38 fitting closely around the hub 2 and against the cylindrical portion 5. This assembly ring carries two long bosses 34^a to provide 15 journal bearings for shafts 34; also two bosses 47^a for support of studs 47 on which are journaled pinions 37, and also two bosses 48^a to support the idler studs 48. The assembly ring is secured firmly in position by 20 the studs 47 and 48 being extended through their bosses on the ring and screwed firmly into the body of the hub below. As a further security, the opposite ends of the studs are held in position by the casing and 25 gear housing 49 which is provided with holes to receive the ends of the studs and support them as shown in Figs. 3 and 4. The housing 49 is flanged where it attaches to the cylindrical portion 5 of the hub and 30 is secured thereto by screws 49^a.

I will now describe my means of producing relative motion between either of the two brake wheels 41 and 43 and the propeller hub.

35 The crank case 50 (or other fixed structure from which the shaft 1 protrudes) has secured to it by brackets 50^a the brake band housing 51 which provides two annular recesses for leather lined brake bands 52 and 40 53. Each band 52 and 53 is secured at one end to the housing 51 as shown at 55 in Fig. 5, from which point they lie closely around in their recesses in circular form with their free ends protruding from the housing 45 through apertures 56 and 57. On the periphery of the housing and between the apertures mentioned there is mounted an operating lever 60 having alternative fulcrums in pins or studs 61 and 62 which 50 are firmly inserted in the lever and which rest at the bottom of double slots 63 and 64 formed in plates 65 and 66, and are held there by the "spring" of bands 52 and 53, whose free ends are connected with studs 61 55 and 62. The plates 65 and 66 are firmly secured to lugs 60^a and 60^b carried by the housing 51, with sufficient space between them to receive the thickness of the lever 60. The lever is operated from its upper 60 end by means of any suitable rod or mechanism engaging the eye 67 (Fig. 12) and capable of thrusting the lever in either direction at the operator's will. When the lever is moved to the right the stud 61 65 remains in the bottom of slots 63 while stud

62 moves towards the top of slot 64 and thus tightens the brake band 52. Similarly, a movement of lever 60 to the left tightens brake band 53.

The position of the brake housing 51 relative to the propeller shaft is such that when the propeller is mounted the brake wheels 41 and 43 will be in position to be engaged by the bands 53 and 52 respectively, whenever either of these bands shall be contracted by operation of lever 60.

The propeller being mounted and in operation, the adjusting or reversing of the blades is accomplished by thrusting lever 60 momentarily in one direction or the other, 75 according to the effect desired. The gripping of one of the brake wheels causes relative motion between it and the revolving propeller, thus setting the various gears in motion and adjusting the blades.

What I claim is:—

1. A propeller comprising a hub, a plurality of ferrules rotatably mounted therein, a blade secured in each ferrule, and thrust bearings between each ferrule and the hub 90 for resisting both inward and outward radial movement of the blades relative to the hub, the major portion of each of said ferrules lying radially beyond and substantially outside of said hub.

2. A propeller comprising a hub, a plurality of ferrules rotatably mounted therein, a blade secured in each ferrule, a radial annular flange carried by each ferrule substantially at its inner end, and thrust bearings between said flange and hub, said ferrules having the major portion thereof projecting outside of said hub.

3. A propeller comprising a hub, a plurality of ferrules rotatably mounted therein, a blade secured in each ferrule, a radial integral annular flange carried by each ferrule adjacent its inner end, and anti-friction thrust bearings on both sides of said flange, 105 between the flange and hub.

4. A propeller comprising a hub, a plurality of ferrules rotatably mounted therein, a blade secured in each ferrule, a radial annular flange carried by each ferrule, gear teeth formed on the periphery of said flange, 110 and means engaging said teeth for rotating the blades on their axes.

5. A propeller comprising a hub, a plurality of ferrules rotatably mounted therein, a blade secured in each ferrule, a complete gear wheel carried by each ferrule, and a second gear engaging said wheel for rotating the blades on their axes, said last named gear being arranged rearwardly of the axes 120 of said blades.

6. A propeller comprising a hub, a plurality of ferrules rotatably mounted therein, a blade secured in each ferrule, a worm wheel carried by each ferrule, a worm engaging each worm wheel, and means for ro- 130

tating said worms to adjust the blades on their axes.

7. A propeller comprising a hub, a plurality of blades mounted therein so as to be capable of rotation on their own axes, and means for so rotating said blades, such means comprising two separate sets of worms and worm wheels for each blade, arranged in series.

10 8. A propeller comprising a hub, a plurality of blades mounted therein so as to be capable of rotation on their own axes, and means for so rotating said blades, such means comprising a gear, a pinion for each 15 blade meshing with said gear, and gearing comprising two sets of worms and worm wheels between each pinion and its corresponding blade.

9. A propeller comprising a hub, a plurality of blades mounted therein so as to be capable of rotation on their own axes, and means for so rotating said blades, such means comprising a gear concentric with 20 said hub, a pinion for each blade meshing 25 with said gear, and gearing comprising a worm and worm wheel between each pinion and its corresponding blade.

10. A propeller comprising a hub, a plurality of blades, carried thereby, and mounted 30 for rotation on their own axes, and means for so rotating said blades in either direction, such means comprising a pair of gears 35 concentric with the hub, a pair of pinions for each blade meshing respectively with said gears and with each other, and means 40 for transmitting the movement of one of said pinions to the blade.

11. A propeller comprising a hub, a plurality of blades carried thereby, and mounted 40 for rotation on their own axes, and means for so rotating said blades in either direction, such means comprising a pair of gears 45 concentric with the hub, gearing connecting each of said gears with all of said blades, a pair 50 of brake wheels rigid with said pair of gears, brake bands for said wheels having one end fixed, and a lever attached to the other ends of said bands, said lever being mounted for pivotal movement about its 55 point of attachment to either band to tighten the other band.

12. The herein-described method of securing 55 a wooden blade shank in a double tapered ferrule having a constricted middle portion, which consists in making the shank of double tapered form similar to the ferrule, and having an enlarged end, compressing such enlarged end and forcing it through the constricted portion of the ferrule, and then expanding such end to fill the tapered portion of the ferrule.

13. The herein-described method of secur-

ing a wooden blade shank in a double tapered ferrule having a constricted middle portion, which consists in making the shank 65 of double tapered form similar to the ferrule, but with its smallest diameter larger than the constricted portion of the ferrule, and having an enlarged end, compressing such enlarged end and forcing it through 70 the constricted portion of the ferrule, while compressing the smallest part of the shank to fit such constricted portion, and then expanding said enlarged end of the shank 75 to fill the tapered portion of the ferrule. 75

14. In a propeller a double-tapered ferrule having a constricted portion, and a blade having a double tapered shank substantially filling said ferrule, with the material of the shank compressed where it lies 80 within the constricted portion of the ferrule.

15. In a propeller construction, a shaft, a propeller hub mounted thereon, a plurality of ferrules rotatably mounted in said hub, a blade secured in each ferrule, a radial annular flange carried by each ferrule, gear teeth on said flange, and means for 85 engaging said teeth and rotating said ferrules and blades, said means being arranged externally of said shaft. 90

16. A propeller construction comprising a hub having a plurality of shallow sockets, a ferrule rotatably mounted in each of said sockets, a blade secured in each ferrule, a radial annular flange carried by each ferrule substantially at its inner end, said hub having two spaced integrally connected flanges surrounding each of said sockets and between which said first named flange is arranged, and thrust bearings between said 95 first named flange and the flanges on said hub. 100

17. A propeller construction comprising a shaft, a hub, a plurality of ferrules rotatably mounted on said hub, a blade secured 105 in each ferrule, a gear wheel carried by each ferrule, and gear mechanism for rotating said gear wheels, said gear mechanism being arranged rearwardly of the axes of said blades and externally of said shaft. 110

18. A propeller comprising a hub, a plurality of blades mounted thereon so as to be capable of rotation on their own axes, and means for so rotating said blade, said means comprising two separate sets of 115 worms and worm wheels for each blade arranged in series, means for causing simultaneous rotation of each of said sets of worms and worm wheels in one direction, and other means for causing simultaneous 120 rotation of each of said sets of worms and worm wheels in the opposite direction.

In testimony whereof I affix my signature.

SPENCER HEATH,
